United States Patent Office.

JOHN JOHNSON, OF NEW YORK, N. Y.

Design No. 3,045, dated May 12, 1868.

DESIGN FOR A STEAM-VALVE CASE.

The Schedule referred to in these Letters Patent and making part of the same.

TO ALL WHOM IT MAY CONCERN:

Be it known that I, JOHN JOHNSON, of the city and State of New York, have invented or produced a new and original Design for a Steam-Valve Case; and I do hereby declare the following to be a correct description of the same, reference being had to the annexed drawing, making part of this specification, in which—

Figure 1 is a side view of said valve-case, and

Figure 2 is an inverted plan of the same.

The wheel *a* for the hand, stem *b*, and polygonal couplings *c c*, are of usual character.

My particular production relates to the shape and configuration of the case within the red line, fig. 1.

The general form of said case is that of a cylinder, *d*, at right angles to the axis of the cock, the upper end of which cylinder is flanged at *e*, for the reception of the polygonal screw-cap, *f*, that is drawn down to the neck, *g*. The closed end, *h*, of said cylinder is made as a flattened dome. The cylindrical portions, *i i*, uniting the cylinder *d* to the polygonal couplings *c c*, are curved at the groins or points of union.

What I claim, and desire to secure by Letters Patent, is—

The design of the shape and configuration of the valve-case, described and represented.

In witness whereof, I have hereunto set my signature, this ninth day of March, 1868.

JOHN JOHNSON.
